Application filed July 18, 1896. Serial No. 599,743. Term of patent 14 years.

To all whom it may concern:

Be it known that I, ADOLF MENTE, a citizen of Bremen, residing at Bremen, Albertstrasse 57^a, Germany, have invented a new and original Design for a Packing-Pot, of which the following is a full, clear, and exact specification.

The pot is wide open at the top and provided here with a groove running all around

this opening on purpose to fasten the covering.

What I claim is—

The design for a packing-pot substantially as shown and described.

In testimony that I claim the foregoing as my invention I have signed my name in presence of two subscribing witnesses.
